SWINGABLE MATERIAL HANDLING UNITS FOR LIFT TRUCKS

Fred J. Avery, La Grange, Ill., assignor of one-half to Hugo L. Kuehlthau, Cook County, Ill.

Application December 28, 1951, Serial No. 263,818

5 Claims. (Cl. 214—653)

This invention relates to swingable material handling units, and more particularly to a unit for use on lift trucks to load and unload material at the side of the truck.

In storing materials such as barrels, cartons, pallet loaded materials and the like in warehouses and in removing such materials from warehouses it is desired to minimize the required aisle width to make maximum use of the storage space. With conventional lift trucks which load and unload only from the front it is necessary to provide aisles wider than the truck length to provide the necessary room for maneuvering the trucks at right angles to the rows of stored material.

It is accordingly one of the objects of the present invention to provide a swingable material handling unit by means of which loads can be stacked or picked up from the side of the truck and can be carried at the front of the truck in the normal position. In this way, the aisles need be only slightly wider than the width of the truck and utilization of the storage space is greatly increased.

Another object is to provide a material handling unit in which the load supporting elements are carried by a supporting plate which can be swung bodily to one side of the truck and turned to different angles when so swung. In this way complete and accurate control of the load is obtained for stacking or picking up.

Still another object is to provide a material handling unit in which a supporting plate is pivotally mounted on an arm which is, in turn pivoted to one side of the truck mounting plate and separate motors are provided to control swinging of the arm and swinging of the supporting plate.

According to one feature, the arm lies near the top of the mounting plate and the supporting plate has a horizontal forward projection at its top through which it is pivoted to the arm so that the support point for the supporting plate is positioned outwardly therefrom toward the center of gravity of the load.

According to another feature, the load supporting elements are clamp arms slidable horizontally on the supporting plate to grip a load between them and a motor is provided on the supporting plate to move the clamp arms.

The above and other objects and features of the invention will be more readily apparent from the following description when read in connection with the accompanying drawings in which:

Figure 1 is a side elevation of a truck equipped with a material handling unit embodying the invention;

Figure 2 is a front view of the truck;

Figure 3 is a partial top plan view, and

Figure 4 is a view similar to Figure 3 showing the parts in a different position.

The material handling unit of the present invention is adapted to be applied to a conventional industrial truck having a body indicated generally at 10, supported on rear wheels 11 and front steerable wheels 12. The

2

body may carry an operator seat 13 adjacent to which is mounted a steering wheel 14 for steering the truck and controls for the motors described hereinafter. At the front of the truck are a pair of spaced vertical guide beams 15 on which a mounting plate 16 is supported for vertical movement thereon. It will be understood that the mounting plate can be shifted to any desired vertical position through the usual power mechanism not shown.

10 The material handling unit of the present invention comprises an arm 17 which is L-shaped and which has one leg thereof pivoted on a vertical axis in a tubular support 18 carried by the mounting plate. Preferably the unit includes a base plate 19 which can be rigidly attached to or detached from the truck mounting plate 16 and on which the tubular support 18 is carried. In use the base plate 19 forms, in effect, a rigid part of the mounting plate 16 and moves vertically therewith at all times.

At its outer end the upper leg of the L-shaped arm 17 carries a vertical bearing 21 in which the upper end of a supporting plate 22 is mounted. Preferably the supporting plate 22 has a forwardly extending horizontal bracket 23 at its top which rigidly carries a stub shaft which is journaled in the bearing 21. With this construction the mounting point for the supporting plate is positioned forwardly thereof to lie close to the center of gravity of a load to be handled so that the tilting load on the bearing 21 will be reduced.

The supporting plate is adapted to carry any desired type of load engaging elements for picking up and transporting a load. For purposes of illustration the load engaging elements are shown as being of a type adapted to handle conventional barrels or drums 24 which are

30 to be stacked at the sides of the aisles in a warehouse. For this purpose, the load engaging elements comprise vertically spaced clamping arms 25 which are rigidly secured to the supporting plate 22 and which are spaced vertically to engage a barrel or drum above and below the center thereof. In the preferred construction the supporting plate 22 is provided with a pair of transversely extending rails 26 on which the clamps 25 fit slidably and the clamps and rails may be provided with registering openings to receive fastening pins for holding the clamps 25 stationary.

40 The rails also support in facing relation to the clamps 25 a pair of vertically spaced clamps 27 which are slidable on the rails 26. The clamps 27 are adapted to be moved toward and away from the clamps 25 by means of a fluid motor 28 which is connected at one end to the supporting plate 22 and at its opposite end to the clamps 27 so that as fluid is supplied to the motor 28 the clamps 27 will be slid toward or away from the clamps 25 to grip or to release a load.

45 The position of the arm 17 about its pivot is controlled by an expandable fluid motor 29 which as best seen in Figures 3 and 4, is pivoted at one end to the mounting plate or base plate 19 at the side thereof opposite to the vertical sleeve 18 and at its other end to the central part of the upper horizontal leg of the arm 17. When the motor 29 is contracted as by admission of operating fluid to its outer end, the supporting plate 22 will be drawn in against the base plate 19 so that the clamping arms project forwardly from the truck in the normal position.

50 When the motor 29 is expanded as shown in Figure 4, the arm 17 will be swung outward to swing the supporting plate 22 bodily away from and to one side of the truck.

55 The angular position of the supporting plate about the bearing 21 is controlled by a similar expandable fluid motor 31 which is pivoted at one end to a bracket 32 on the arm 17 and at its opposite end to the hori-

70

zontal flange 23 at a point spaced from the bearing 21. As the motor 31 is expanded or contracted by admission of operating fluid to its opposite ends it will swing the supporting plate 22 about the pivot 21 to position it accurately in any desired position.

In using the device as for example, in a warehouse wherein barrels as shown at 24 are to be stacked, the truck may move straight down an aisle with the handling unit in the position shown in Figures 1 and 3. A barrel to be stacked may be carried by the clamping arms 25 and 27 at this time. When the truck reaches the desired position at which the barrel or drum is to be stacked, the parts may be swung to the position shown in Figure 4 to place the clamping arm and the barrel at one side of the truck. By controlling the motors 29 and 31, the barrel can be accurately positioned to be stacked on a barrel already in place as shown, for example, in Figure 2 in dotted lines. When the barrel is so positioned and at the required height, the clamping arms 27 and 25 may be opened to release the barrel and the clamp unit may be swung back to the position shown in Figure 3. To remove a barrel from a stack this procedure is reversed, the clamping unit preferably being swung back to the position shown in Figure 3 after the barrel has been picked up for transporting it.

Other types of loads, such as cartons, can be handled in a similar manner. For material loaded on pallets the clamping arms 25 and 27 may be replaced by forks which will slip under and support the pallets in the usual manner. In any case regardless of the type of load it can be quickly and accurately swung out to one side of the truck for stacking or for removing load units from stacks. In all cases, the aisle width need be only slightly greater than the width of the truck since the truck can handle the loads accurately and quickly without being required to turn.

While one embodiment of the invention has been shown and described in detail, it will be understood that this is illustrative only and is not to be taken as a definition of the scope of the invention, reference being had for this purpose to the appended claims.

What is claimed is:

1. A swingable material handling unit for mounting on the mounting plate of a lift truck comprising an arm adapted to be pivotally mounted on a vertical axis at one side of the mounting plate to project horizontally therefrom, a supporting plate pivotally mounted at the free end of the arm on a vertical axis, load engaging elements on the supporting plate to engage and support a load, a first motor connected to the arm and the mounting plate to swing the arm about its vertical axis to move the arm from a position in which the supporting plate lies substantially flat against the mounting plate to a position spaced outward from and at said one side of the mounting plate, and a second motor connected to the arm and the supporting plate to swing the supporting plate about its pivotal connection to the arm.

2. A swingable material handling unit for mounting on the mounting plate of a lift truck comprising an arm adapted to be pivotally mounted on a vertical axis at one side of the mounting plate to project horizontally therefrom, a supporting plate pivotally mounted at the free end of the arm on a vertical axis, a first motor connected to the arm and the mounting plate to swing the arm about its vertical axis to move the arm from a position in which the supporting plate lies substantially flat against the mounting plate to a position spaced outward from and at said one side of the mounting plate, a second motor connected to the arm and the supporting plate to swing the supporting plate about its pivotal connection to the arm, a pair of clamp arms mounted on the supporting plate for relative horizontal movement toward and away from each other, and a third motor on the supporting

plate to move the clamp arms relatively toward and away from each other.

3. A swingable material handling unit for mounting on the mounting plate of a lift truck comprising an L shaped arm one leg of which is adapted to be mounted on a vertical axis at one side of the mounting plate with the other leg extending horizontally from its top, a vertical supporting plate having a horizontal outward projection at its top pivoted on a vertical axis to the free end of said other leg, load engaging elements carried by the supporting plate, a first motor connected to the arm and the mounting plate to swing the arm about its vertical axis to move the arm from a position in which the supporting plate lies substantially flat against the mounting plate to a position spaced outward from and at said one side of the mounting plate, and a second motor connected to the supporting plate and the arm to swing the supporting plate about its pivotal connection to the arm.

4. A swingable material handling unit for mounting on the mounting plate of a lift truck comprising an L shaped arm one leg of which is adapted to be mounted on a vertical axis at one side of the mounting plate with the other leg extending horizontally from its top, a vertical supporting plate having a horizontal outward projection at its top pivoted on a vertical axis to the free end of said other leg, an expansible fluid motor pivoted at one end to said other leg intermediate its ends and at its other end to the other side of the mounting plate to move said other leg from a position in which the supporting plate lies substantially flat against the mounting plate to a position spaced outward from and at said one side of the mounting plate, a second expansible fluid motor connected at one end to the arm and at its other end to the supporting plate at a point spaced from its pivotal mounting on the arm, a pair of clamp arms mounted on the supporting plate for relative horizontal sliding to grip a load between them, and a motor on the supporting plate to move the clamp arms toward and away from each other.

5. In combination with a lift truck having vertical guides and a mounting plate slideable vertically on the guides, a material handling unit comprising an arm pivoted on a vertical axis at one side of the mounting plate and extending horizontally adjacent the top of the mounting plate, a supporting plate pivoted on a vertical axis at the free end of the arm, a first motor connecting the arm and the mounting plate to swing the arm about its pivot, a second motor connecting the arm and the supporting plate to swing the supporting plate about its pivotal connection to the arm, a pair of clamp arms mounted on the supporting plate for relative horizontal sliding to grip a load between them, and a motor on the supporting plate to move the clamp arms toward and away from each other.
